UNITED STATES PATENT OFFICE.

LOUIS JANOIR, OF ST.-OUEN, FRANCE.

LATCH.

Application filed August 22, 1927, Serial No. 214,767, and in France August 27, 1926.

The present invention has for its object the provision of a latch more particularly applicable for fastening the doors of motor car bodies.

5 The latch is of such construction that its bolt is constituted by a rod or stem at right angles to the door, capable of rotation and provided with side projections, which, upon closing of the door, encountering abutments 10 carried by the keeper, pass over these abutments, by causing the bolt to turn, and fall back behind these abutments under the action of a spring.

15 Preferably, the side projections of the bolt have the general shape of wedges, the points of which are set in the returning direction of the bolt and the abutments of the staple are constituted by wedges 20 transversely set.

20 Owing to these arrangements, the latch in accordance with the invention ensures a closure without play, whatever may be the degree of wear of the members in contact, the fastening of the door against the fixed corresponding part being always realized by the action of the spring on the bolt.

25 Another feature of the latch in accordance with the invention consists in the arrangement of the door and the fixed corresponding part, of tapered male and female members, respectively, concentric with the bolt, which fit into each other upon closing, ensuring at the same time the centering.

30 The accompanying drawing illustrates, by way of example, one of the forms of execution of the latch in accordance with the invention.

35 Fig. 1 is a front view of the keeper.

40 Fig. 2 is a longitudinal section of the latch through an axial plane; it shows the latch before engagement.

45 Fig. 3 is a section similar to the preceding one, but it shows the latch after engagement.

Fig. 4 is a diagrammatic end view of the bolt.

50 The door 1 carries a casing 2 wherein is journalled, at right angles to the door, a cylindrical rod 3 constituting the bolt. The rod 3 can rotate about its axis, but is prevented from having any longitudinal movement by a suitable abutment, such as a lever 4 rigidly mounted on the said rod and held between the door and the casing 2. The rod 3 is brought back, in the direction of the arrow *b* (Fig. 3), by a spiral spring 5 (Fig.

4), or any other resilient means, acting on the lever 4.

Opposite the bolt, the door frame receives the keeper 6, perforated with a circular opening on the walls of which are distributed abutments 7, of wedge shape having side faces constituted by helical inclines 7^a, 7^b.

55 The corresponding end of the bolt 3 carries side projections 8 (Fig. 4) having a shape similar to that of the abutments 7. However, the wedges which are formed by the projections 8 are set in reverse direction to those constituting the abutments 7, that is to say their points are turned towards the direction in which the bolt is turned by the 60 spring 5. The other end of the bolt is provided with an operating handle (not shown).

65 Concentrically with its central opening, the staple is provided with a female frusto-conical bearing portion 9 to which corresponds, on the casing 2, a male frusto-conical bearing portion 10. Near the end of this male bearing portion, the casing is transversely cut away for giving passage to the 70 abutments of the keeper, upon closing of the door.

75 When the door is pushed, the side projections of the bolt come in contact with the abutments of the keeper. The inclines, 80 forming the side-faces of the said side projections and abutments, determine the rotation of the bolt in the direction of the arrow *a* (Fig. 2), during the time the door continues its movement. At the same time, the 85 spring 5 is put under tension and as soon as the projections of the bolt have passed beyond the points of the abutments of the keeper, they fall back behind these abutments and the spring 5 brings back the bolt 90 in the direction of the arrow *b*. By pressing against each other the respective bearing portions of the casing and of the staple prevent rattling, owing to their tapered form and the snug engagement effected by the projections 8 and the abutments 7.

95 The returning movement of the bolt by the spring 5 is not limited in a positive manner; therefore, it stops only when the bearing portions of the casing and of the keeper 105 are firmly pressed against each other, thus doing away with play.

100 Opening of the door is effected by turning the handle in the direction of the arrow *a* and by pulling the door open.

It is obvious that the directions of rotation can be reversed according to the shape or the arrangement of the handle. Moreover, the invention is not, of course, limited 5 to the exact details of construction described and illustrated. Thus, the male and female bearing portions of the casing and of the keeper can have another shape than that of a frustum and can be of cylindrical, cylindro-conical, spherical or like shapes, provided the two corresponding parts are capable of snug interfitting with each other.

I claim:

15 A latch for motor car body and other doors, comprising a rotating bolt subjected to the reaction of a spring and a fixed keeper for receiving the said bolt, a member for anchorage on the door and provided with a conical nipple drilled in order to serve as a

bearing for the front part of the bolt, a keeper for anchorage on a part fixed with respect to the door and provided with a circular recess enlarged at its front part for providing a conical surface upon which the conical nipple takes a bearing when the door 25 is closed, radial protruding parts on the bolt having two faces converging in the direction of the rotation of the bolt when the same is acted upon by the spring, radial corresponding protruding parts provided on the keeper internally to the circular recess of the latter, and having faces converging in an opposite direction to the corresponding faces of the protruding parts of the bolt.

In testimony whereof I have signed my 35 name to this specification.

LOUIS JANOIR.
